(57) **CLAIM**

The ornamental design for an applicator device, as shown and described.

DESCRIPTION

FIG. 1 is a front view of an applicator device of the present invention.

FIG. 2 is a rear view of the applicator device of FIG. 1.

FIG. 3 is a top plan view of the applicator device of FIG. 1.

FIG. 4 is a bottom view of the applicator device of FIG. 1.

FIG. 5 is a right side view of the applicator device of FIG. 1.

FIG. 6 is a left side view of the applicator device of FIG. 1.

FIG. 7 is a perspective view from above of the applicator device of FIG. 1.

FIG. 8 is a perspective view from below of the applicator device of FIG. 1; and,

FIG. 9 is a front view of the applicator device of FIG. 1, wherein a top part of the device is pressed down so that, for example, when the device has been located on the human body over a microneedle array, pressing the top part down applies the microneedle array to the skin.
